UNITED STATES PATENT OFFICE.

GEORGE WILLIAM GROSVENOR, OF KIDDERMINSTER, ENGLAND.

LOOM FOR WEAVING TUFTED FABRICS.

SPECIFICATION forming part of Letters Patent No. 669,634, dated March 12, 1901.

Application filed December 18, 1897. Serial No. 662,450. (No model.)

To all whom it may concern:

Be it known that I, GEORGE WILLIAM GROSVENOR, a subject of the Queen of the United Kingdom of Great Britain and Ireland, 5 residing at Kidderminster, in the county of Worcester, England, have invented certain new and useful Improvements in Looms for Weaving Tufted Fabrics, (for which I have obtained Letters Patent of the United Kingdom of Great Britain and Ireland, dated June 22, 1896, No. 13,747,) of which the following is a specification.

This invention relates to the manufacture of piled or tufted carpet fabrics known as 15 "Moquettes" or "Royal Axminster" carpets; and it has for its objects to produce a more equal division of the pile or tufts by the wefts than heretofore, to effect at the same time a saving of the pile-yarn, and by a part of the 20 means employed to attain the aforesaid objects to gain time for the movement of the bobbin carrier or chains, thereby enabling the loom to be driven at a higher rate of speed than usual, with the result of obtaining an 25 increased output.

The stitch or weave herein described and forming a part of my invention is a variation of Figure 2 of F. B. Fawcett's specification, No. 9,665 of 1893, and by aid of the herein- 30 described means and the usual intervening mechanism it is intended to weave the improved fabric on the looms described in the Specification No. 21,896 of 1895, which is in the names of myself and the aforesaid F. B. 35 Fawcett.

In the further description of this invention reference is made to the accompanying drawings, in which—

Fig. 1 is an elevation of one of two improved cams for operating the binding-warp, 40 the two cams being made alike, but placed oppositely on the loom in the well-known manner. These cams are referred to herein- 45 after as cams A and A'. Fig. 2 is an elevation of an improved cam, to be known as "cam C," for actuating the transferring-arms. Fig. 3 is an elevation of an improved cam D for working the weft carrier or needle. Fig. 4 is an elevation of an improved cam E 50 for operating the dead-warp. Fig. 5 is a partial view of the left side of the loom, showing a finger F used for dividing the weft-

thread and a cam G and intervening mechanism for operating the said finger. Fig. 6 is an elevation of an improved cam L for 55 actuating the small selvage-shuttle to work in combination with the finger. Fig. 7 is an elevation of an improved cam M for slackening the weft while the finger F is pushing the weft-thread into place. Fig. 8 is a detailed 60 elevation of the lever H shown in Fig. 5. Fig. 9 is a plan of a portion of the fabric, and Fig. 10 is a longitudinal section of a part of the fabric, both on an enlarged scale. In Fig. 9 the first shot or back weft is omitted 65 for the sake of clearness. Fig. 11 is an end elevation of the loom, showing the cam-shaft with cams thereon. Fig. 12 is a plan of a portion of the width of the fabric, similar to Fig. 9, but extended to show the selvage catch-thread running out of hole in a small shuttle to catch the loop in the doubled weft, the shuttle actuating mechanism being omitted for clearness. Fig. 13 is a plan of the fabric, several of the warps being omitted, 70 showing the aforesaid doubled weft held apart by the finger F shown in Fig. 5. Fig. 14 is an elevation, on an enlarged scale, 75 of the finger F and the lever H for actuating the same, clearly indicating the means for 80 adjusting the length of the stroke of the said finger.

In the class of looms above referred to the pile or tufted material is carried in bobbin-tubes, from the lower end of which the pile 85 projects as it is drawn from the bobbins. The projecting ends of the pile therefore are put down in position between the warp-threads, after which a shot of weft is introduced into the shed to secure and fasten the ends of the 90 pile or tufting material, and those ends are then turned backward and upward by means of a comb previous to the introduction of the next shot, after which the pile is cut. Consequently the class of looms and the fabrics 95 made thereon differ from those formerly used, wherein the tuft-yarn was drawn from spools by clamps and then cut off the proper length and inserted in the warp by nippers, as described in the United States Patent to Albert 100 L. Skinner, No. 330,069, dated November 10, 1885, or the fabric described in the United States Patent to Robert F. Patterson, No. 432,763, dated July 22, 1890, in which each

shed contained three shots of filling, each shot inserted double and the pile or tuft going around one of the upper double shots, while the next upper doubled shot was inserted and beaten up to hold the tuft in place, or in a similar fabric shown in Fig. 5 of the United States Patent to Richard B. Loynd, No. 436,529, dated September 16, 1890, or in other cases in which the pile at its root had to pass around two threads of weft, so that the two halves or projecting ends of the pile were kept apart by the width or space occupied by the doubled weft; but by this invention I split or separate the two or double weft-threads thrown as a single shot above the dead-warp after their insertion by means of the ordinary selvage-shuttle pausing in the loop of the weft and of a finger F, placed on the left side of the loom, Fig. 5, similar to the one previously in use on the opposite side, the said finger F being caused to push that thread of the weft which is nearest to the front of the loom nearly into the place it will subsequently occupy when beaten up by the lay, while leaving the other weft-thread stationary where inserted. This leaves a space between the two wefts in which the bobbin-tubes x', Fig. 11, with the pile ends x, Figs. 5 and 11, may be pushed through the warps. The lay is then caused to beat up the other thread of weft to bind the pile, and the comb afterward turns up the pile ends in the usual way, except only that they are turned around one thread of the weft instead of two, as formerly. The back weft is previously inserted, as in the two-shotstitch, Fig. 2, of the aforesaid No. 9,665 of 1893.

The improved cam A, Fig. 1, and its duplicate A' are mounted oppositely (as aforesaid) on the loom in the well-known manner, and they are used for operating the heddles which carry the binding-warps. The arrow shows the direction of motion of the cam A, and beginning at the point marked a and extending to the point b the first shot or back weft z is inserted, the warp z⁴ being held down by the cam A'. Between b and the point c the second or upper shot of weft y is inserted, the warp being still held down. Between c and d the warps z' and z⁴ are leveled to enable the pile ends x to be pushed through the warps and the separated or split threads of the said upper shot of weft y by means of the transferring-arms, and from d to e the warps z' and z⁴ are reopened to allow the slack of the separated weft-thread y (which is to hold the pile) to be drawn tight from the left selvage by the ordinary apparatus for that purpose. Between the points e and f the warps z' and z⁴ are leveled to enable the comb to push up the pile ends x to the surface, a process described in Fawcett's aforesaid specification, No. 9,665, of 1893. From f to g the warp z⁴ is raised by the cam A' to admit the first or back weft shot x again, and from g to h the warp z⁴ remains up for the insertion of the second or upper shot of weft y. Between h and i the warps z' and z⁴ are

again leveled for the insertion of the pile ends x, and between i and j the warps z' and z⁴ are reopened for tightening the weft-thread y. Then from j to k the warps z' and z⁴ are leveled for the comb to push up the pile ends x, as before, which completes the cycle of operations performed by the cam A. As indicated above, the duplicate cam A' operating the warp z⁴ performs the same cycle of operations; but they are both put on the treadle-box of the loom with corresponding points opposite to each other, so that the cycle of operations of each cam differs from the other in point of time by one-half a revolution. Thus the cams A A' being caused to operate the heddles which carry the binding-warp, one half of the warp-threads z' are raised by the cam A, while the other half of the warp-threads z⁴ are lowered by the other cam A' in the well-known manner; but it is to be noted that the cams A and A' differ from the cams hitherto used by providing for reopening the warps to enable the weft-thread to be drawn tight.

A cam B is used for advancing the bobbin carrier or chains; but it is practically the same as the cam B shown in Fig. 2 of Grosvenor and Fawcett's specification, No. 21,896, of 1895. It is, however, adjusted to work in accordance with the general sequence of motions followed in the present invention.

Fig. 2 indicates a cam C, altered to work the transferring-arms in accordance with the motions produced by the improved cams A and A'. The transferring-arms are required to move the bobbin, with the projecting pile ends, to and from the chains and to push the pile ends through the warps and the separated or split weft-threads to the weaving-point, and the cam C is altered from the similar cam C, Fig. 3, in Grosvenor's and Fawcett's aforesaid specification, so as to make the transferring-arms remain a little longer up at the chains, as they have to wait until the upper shot of weft is inserted and while the doubled weft-thread is separated or split before they can move the bobbin down to push the pile ends through. In addition to the said alteration the cam C is adjusted to work in accordance with the motions produced by the aforesaid cam B. The improved cam C of the present invention is so made that from the point l, Fig. 2, to the point m is produced no movement of the usual mechanism employed, the idle time permitting the chains to advance the next bobbin by means of the aforesaid cam B; but at the point m the transferring-arms are caused to seize a bobbin on the chains and from there to the point marked n take the bobbin down for the weaving process. Between n and o the pile ends x are pushed through the warps and the separated or split weft by the operation of the cam C; but from thence onward to p the operations of placing the pile ends x, Fig. 9, against the pushed-up thread of second weft-shot and a previously-inserted

row of pile, causing the comb to turn up the pile ends to the surface, lifting the transferring-arms a little to draw the pile off the bobbin and cutting the pile by the knives, are all 5 performed by contributory cams. Between *p* and *l*, Fig. 2, the cam C operates the transferring-arms to take a bobbin back and replace it on the chains, which completes the 10 cycle of operations performed by the cam C; but in combination therewith there are other 15 cams which by the motions they produce are contributing to its operations, as they cause the transferring-arms to seize and replace the bobbin at the chains and rock the bobbin 20 when the pile ends are pushed through the warps and the separated or split wefts. The aforesaid contributory cams, however, are not shown, as they are all of the usual construction, but require adjustment on the loom 25 to work in unison with the altered and improved cam C, and the cam B as part of the sequence of motions producing the improved general result.

In Fig. 3 an improved cam D is shown, 25 which is very similar in its form, and consequently in the operations performed by it, to the cam D shown in Fig. 4 of the aforesaid Grosvenor and Fawcett's specification, No. 21,896 of 1895. The cams are alike in having 30 the same lever arrangement and in giving more scope and ease in working the weft carrier or needle at a high speed and in imparting but two insertions of weft in its revolution, unequal intervals of idle time being provided for in its revolution. In the cam D, 35 however, of the present invention the intervals of idle time, though still unequal, do not differ so much as in Grosvenor and Fawcett's cam D, because in this case the upper weft has to be inserted before the bobbin comes 40 down to push through the pile ends and is not delayed until afterward, as in the former case. Consequently the long interval of idle 45 time between the weft insertions is proportionately reduced. Furthermore, the present cam D is fixed on the loom in a position to differ by half a revolution from the relative position of Grosvenor and Fawcett's cam D, so that the shorter interval of idle time comes between 50 the insertion of the back and upper wefts for the same stitch or row of pile and the longer 55 interval of time between the insertion of the upper and back wefts or the finishing and beginning of a stitch or row of pile. By a suitable adjustment of the cam D this latter 60 interval occurs in the sequence of motions while the chains are being advanced and during the subsequent tufting motions, thus affording the requisite time for performing 65 these movements before the next back weft (or first shot of a stitch) is inserted. In the drawing of the cam D, Fig. 3, *r* indicates the point on the cam at which the needle begins 70 to insert the second shot or upper weft, the 75 cam rotating in the direction of the arrow, the operation being finished at *s*, and after which the separation or splitting of the upper

weft takes place. Between *s* and *t* the needle is withdrawn from the shed, and from *t* to *u* the longest interval of idle time occurs, this 70 being the termination of the stitch, as above stated. The next stitch then begins, the needle inserting the back weft (or first shot) between *u* and *v*, between *v* and *w* the needle is withdrawn from the shed, and from *w* to *r* 75 occurs the short interval of idle time for the needle, which completes the cycle of operations of cam D.

Fig. 4 represents an improved cam E, used 80 for operating the heddle carrying the dead warp (or stuffer) inserted in the woven fabric. At the point marked *a'* in the drawings the dead-warp is raised to allow the insertion of the first shot or back weft between that point and *b'*, while from thence to the point 85 *c'* the dead-warp is lowered for the insertion of the second shot or upper weft. Between *c'* and *d'* the warps are leveled for the pile ends to be pushed through the warps and the separated or split threads of the upper weft, 90 and from *d'* to *e'* the warps are reopened to allow the slack of the separated weft-thread which is to hold the pile to be drawn tight from the left selvage by the ordinary apparatus for that purpose. Between *e'* and *f'* 95 the warps are leveled for the comb to push the pile ends up to the surface. From *f'* to *g'* the dead-warp is raised for a sufficient period to admit the insertion of the next first shot or back weft, and then the cam slopes 100 down to the point *h'* to lower the dead-warp while the next second or upper shot of weft is inserted. Between *h'* and *i'* the warps are again leveled for the insertion of the pile ends. From *i'* to *j'* they are again reopened for 105 tightening the weft-thread, and from *j'* to *k'* the warps are leveled for the comb to push up the pile ends to the surface, the cycle of operations being again repeated from *a'*.

Fig. 5 is a view of the left side of the loom, 110 showing the pivoted finger F, (preferably forked at the end, as shown,) the intervening mechanism for working the same from the cam G consisting of the centrally-pivoted lever H, with its cam-engaging roller at the 115 lower end (shown also in side elevation, Fig. 8) and a rod I connecting the lever H and the pivoted finger F. Means of adjusting the length of stroke of the finger F are provided by a slot in the upper end of the lever 120 H and holes in the lower part of the pivoted finger F, and by means of a pin and nut at each end of the connecting-rod I the latter is pivotally connected at one end to the said lever H at any desired point in the slot, and 125 similarly at the other end in any desired hole of the finger F to give the latter a longer or shorter stroke, as required, the whole being actuated by the cam G, mounted upon the shaft K, revolving in suitable bearings (not 130 shown) carried by the loom-frame J.

In looms of the kind hereinbefore mentioned the wefts are doubled by the manner of their insertion, which is as follows: Each

shot of weft is inserted by the needle, consisting of a long projecting rod connected at its right-hand end to a slide, whereby the needle is moved to and fro in the shed formed by the warps, starting, of course, from the right side of the loom. At the left side or free end the needle is provided with an eye having an opening to the outside to enable the weft-thread to be slipped into the eye by 5 a guide, the weft being supplied from a bobbin or ball set at the right side of the loom. The weft runs through the eye of the needle during its passage through the shed of the warps, so that on its arrival at the opposite 10 or left side of the loom a loop is necessarily formed by the doubling of the weft, through which the ordinary small selvage-shuttle passes, carrying a thread to catch this weft-loop and form a selvage. By this process the 15 weft is held so that the needle can be withdrawn from the shed, leaving the weft behind, while the shuttle also returns to its normal position. In this invention after entering the loop of the weft the shuttle pauses 20 therein (by means of a cam hereinafter described) to keep apart the doubled line of weft in the position shown in Fig. 12, with the outer thread of the doubled weft below the shuttle and the inner thread above it, 25 thus keeping the outer thread of the doubled weft in place to hold the pile, while its continuation or inner line of weft goes over the top of the shuttle at a higher level in position for the finger F to pass over the outer thread 30 and engage with the inner one to separate the two, as shown in Fig. 14. This special action of the shuttle also releases the weft from the needle, so that the latter can be withdrawn from the shed. The inner line or thread of 35 weft being bound in the fabric at the right-hand selvage is the one that can be beaten or pushed up toward the weaving-point, while the outer line or thread of weft remains at the distance from the woven fabric at which the needle inserted it. The two portions of the weft being thus kept apart by the shuttle during 40 its pause in the loop of the doubled weft, as shown in Fig. 12, the finger F advances between the shuttle and the edge of the warps 45 and pushes the upper portion or inner line of weft (which is higher in level than the outer thread by the thickness of the shuttle) for about two inches from the outer line of weft, as shown in Fig. 13, and so leaving sufficient 50 space for the bobbin-tubes x' , Fig. 11, with the pile ends x to be pushed through between them. The finger F pauses after having pushed the inner thread to keep it in place until the warps are tightened upon it by being leveled for the bobbin movement, after 55 which the finger F is withdrawn to its normal position. In the meantime the shuttle completes its passage through the loop of the doubled weft, carrying the catch-thread to 60 form the selvage, and the back weft or first shot is inserted and operated in the usual manner. The inner thread of doubled weft 65

is pushed apart from the outer thread by the finger F by means of the cam G, Fig. 5, between the points x^3 to y^3 through the spring-pressed lever H and rod I, which is the position shown in the drawings. From y^3 to z^3 the finger pauses to hold the pushed thread in place until the warps are leveled, after which it returns to its normal position. 70 75

Fig. 6 shows an improved cam L bolted onto its disk for actuating the small selvage-shuttle in combination with the finger F. By means of this cam and intermediate mechanism the shuttle is caused to move its point 80 under the needle and through the weft-loop from l' to m' and at the latter point to make a very slight pause to release the weft from the eye of the needle by holding the weft back while the needle withdraws from it, as 85 in ordinary looms. Between m' and n' the shuttle moves a farther distance into the weft-loop to put its body therein and then pauses until the point o' is reached, thus holding the doubled threads of weft apart during their 90 separation by the finger F. Then from o' to p' and onward to q' the shuttle completes its passage through the weft-loop, carrying the catch-thread with it, to form the selvage in the usual manner, and from q' to r' the shuttle 95 returns to its normal position. Another cam follows on, being fixed to the other or plain portion of the disk; but it is not shown, as it is of the usual construction. It is used for actuating the shuttle to form the selvage 100 when the first shot or back weft is inserted.

Fig. 7 indicates an improved cam M, used for slackening the upper weft-thread during its insertion by the needle and division by the finger. The weft-thread is normally in 105 a state of tension by a separate and ordinary apparatus; but this cam is adapted to slacken or take off the tension, as required, as beginning at s' the weft-thread is slackened for the insertion of the second shot or upper weft 110 by the needle until t' is reached. Between t' and u' the weft is tightened to insure the point of the shuttle going correctly through the weft-loop, also for the finger F to come 115 in contact with the inner thread. Then from u' to v' it is again slackened for the finger to push the thread. After v' the tension apparatus (not shown) pulls through the shed whatever slack there may be from the left selvage, the heddles being reopened for that 120 purpose.

A partial plan of the fabric is shown in Fig. 9 (but with the first shot or back weft omitted for clearness) and a longitudinal section through one complete stitch in Fig. 10, both 125 views being upon an enlarged scale. In these the pile ends are indicated by x , the looped or doubled weft-thread, which forms the second shot or upper weft, is indicated by y , and in Fig. 10 the first shot or back weft 130 by z . The binding-warps are indicated in both figures by z' and z'' , and the stuffer or dead-warp by z^3 . The looped end of the upper shot of the doubled weft-thread is

clearly shown on the left-hand side of Figs. 9, 12, and 13, and in Fig. 10 it is indicated by the dotted lines, while the pile x is also clearly shown in these figures as inclosing 5 and partly surrounding one portion only of the said doubled thread, the other portion being bound by the warp-threads between contiguous rows of the pile x . The loom being thus provided with the finger F for dividing the doubled weft-thread and with the improved cams A, A', C, D, E, G, L, and M necessary thereto, together with material for weaving, is ready for the adjustment of all the cams to be used, and by reference to the 10 foregoing description and to the example of the two-shot fabric, Fig. 2 of the aforesaid specification, No. 9,665, of 1893, and description of the weaving process any loom-tuner will be able to adapt and adjust the mechanism to the sequence of the required motions. Assuming that a complete stitch has been woven and that the cutting of the previous 15 row of pile by the knives has just taken place, the bobbin is released, ready to be returned to the chains by the transferring-arms. The 20 heddles, which respectively carry the binding-warp z' in Figs. 9 and 10 and the dead-warp z^2 have been raised, while the heddle carrying the binding-warp z^4 has been lowered by the 25 improved cams A, A', and E. The weft-carrier or needle-cam D having just passed its longest interval actuates the needle, inserting the first or back weft z , the lay beats it up, it having passed its shortest interval, and recedes. 30 The heddle is then shifted by the cam E to lower the dead-warp z^2 , the other two heddles remaining in the same position as for the previous shot or back weft, while the needle is again actuated by the improved cam D to 35 insert the second shot or upper weft y after its shortest interval of idle time. The doubled weft of the second shot is then separated or split by the finger F, advancing from the 40 point at which it is shown in Fig. 12 and pushing that portion of the thread which is bound at the right selvage of the fabric nearly into its place, as shown in Fig. 13, leaving the other portion of the upper weft-thread where it was inserted by the needle. This leaves a 45 wide parallel space between the two threads of the weft for the bobbin-tubes x' , Fig. 11, to push the pile ends x through, as shown in Fig. 13. The warps are then put level, the 50 bobbin being returned to the chains in the meantime by the transferring-arms as actuated by the cam C, after which the chains are advanced to bring the next bobbin into position by the cam B. (Shown in Fig. 2 of the specification No. 21,896 of 1895.) The cam C, 55 still rotating, actuates the transferring-arms, which seize the next bobbin and, taking it down, pushes the projecting pile ends through the leveled warps in the space between separated portions of the weft-thread and places 60 the said pile ends against the previously-woven row of pile, the tubes pushing the in-

ner portion of the weft-thread up at the same time. The warps are then reopened to allow the slack of the outer part of the weft-thread to be drawn tight from the left selvage in the 70 usual manner. In the ordinary looms this is done with each shot of weft as soon as it is inserted; but in this case it has to wait to be done after the bobbin movement, and the warps have to be reopened for the purpose. 75 The lay then beats up the outer portion of the weft-thread, which incloses the pile ends between the doubled weft-thread. The transferring-arms are slightly raised to draw the required length of pile off the bobbin, the 80 warps are again leveled for the comb to push up the pile ends to the surface, and the pile is cut, all as in the ordinary way. This brings the loom to the point of exactly repeating the cycle of operations, except that 85 the shifting of the binding-warps is reversed on account of the positions of the cams A and A' on the treadle-box; but in the recurring cycle of operations the binding-warps are again reversed to the position first assumed, 90 and so on. The effect produced is that by thus separating the doubled or two wefts simultaneously inserted a three-shot fabric is practically formed in a two-shot loom, and the said wefts divide the pile singly, as is 95 the case also with some three-shot fabrics wherein each shot is thrown separately, instead of as in some other three-shot fabrics in which the pile is bent around two separately-thrown shots, whereby a more equal division 100 of the pile and a tighter bind are obtained.

The improvements described require the pile-weft to be inserted before the pile ends are pushed through the warps instead of afterward, as heretofore. Consequently this allows 105 the bobbin with the pile ends to remain that much longer on the chains and to give a corresponding increase of time for moving the said chains, of which advantage may be taken by driving the loom at a higher rate of speed. 110

It is to be noted that a longitudinal section taken through a fabric woven in accordance with this invention would in appearance be the same as Fig. 3 of Fawcett's specification, No. 6,158, of 1882; but in this latter case three 115 distinct shots of weft are thrown to one row of pile instead of two only, as in this present invention. Consequently I would have it understood that I do not claim anything described or claimed in the said specification 120 nor in any of the hereinbefore-mentioned specifications.

What I claim as my invention, and desire to secure by Letters Patent, is—

1. In a loom for manufacturing piled or tufted carpet fabrics, the combination of means for working the heddles and warp-threads, and for inserting a doubled or two threads of weft simultaneously, with means such as a finger F for separating or forming a wide space 125 between the said two threads previous to the insertion of the pile ends within the said space, 130

and means for inserting the pile ends between said threads, substantially as and for the purpose herein described.

2. In a loom for manufacturing piled or tufted carpet fabrics, the combination of means for working the heddles and warp-threads, means consisting of a single needle for inserting a doubled or two threads of weft simultaneously, means such as a finger F for separating or forming a wide space between the said two threads, means such as a shuttle carrying a catch-thread to pass through and engage with the loop of the said doubled weft-threads to form a selvage previous to the insertion of the pile ends within the said space, and means for inserting the pile ends between said threads, substantially as and for the purpose herein described.

3. In a loom for manufacturing piled or tufted carpet fabrics, the combination of means for working the heddles and warp-threads, means such as a single needle for simultaneously inserting a doubled or two threads of weft across the fabric in a single shed of the binding-warps, means such as a shuttle and catch-thread to enter the loop of the said weft-threads and cause the shuttle to pause therein, means such as a finger F to pass over one of the said doubled threads and engage with the other thread to separate it from the first during the said pause of the shuttle, and means for inserting the pile ends between said threads, substantially as and for the purpose herein described.

4. In a loom for manufacturing piled or tufted carpet fabrics, the combination of means for working the heddles and warp-threads, means for simultaneously inserting a doubled or two threads of weft across the fabric in a single shed of the binding-warps, means such as a shuttle and catch-thread to enter the loop of the said weft-threads and cause the shuttle to pause therein, means such as a finger F to

pass over one of the said weft-threads and engage with the other to separate the two by a wide space, means to continue the motion of the said shuttle after the said space is formed to make a selvage, and means for inserting the pile ends between said threads, substantially as and for the purpose herein described. 50

5. In a loom for manufacturing piled or tufted carpet fabrics, the combination of means for working the heddles and warp-threads and to insert two weft-threads across the fabric in a single shed, means to separate the said threads, means to form a selvage at one side of the said fabric, means for inserting a row of pile ends between the said threads subsequently to their separation and to turn the said pile ends around one thread, and means to beat up the other thread against the upturned pile ends to keep them in position, substantially as and for the purpose herein described. 55

6. In a loom for manufacturing piled or tufted carpet fabrics, the combination of means for inserting and retaining two weft-threads across the fabric in a single shed, with a finger F pivoted at its lower end, a pivoted lever H and actuating-cam G, a connecting-rod 70 I between the said finger and lever, means for adjustment whereby the length of the stroke of the said finger may be varied to enable it to engage with one thread and separate it from the other by a wide space, and means for inserting the pile ends between said threads, substantially as and for the purpose herein- 75 before described and shown in the drawings.

In testimony whereof I have signed this specification in the presence of two subscr- 80 ing witnesses.

GEORGE WILLIAM GROSVENOR.

Witnesses:

JAMES MORTON,
FRED GADSBY.
